(57) **CLAIM**

The ornamental design for an inhaler, as shown and described.

DESCRIPTION

FIG. 1 is a top, front, right perspective view of an inhaler showing our new design;

FIG. 2 is a front elevation view thereof;

FIG. 3 is a rear elevation view thereof;

FIG. 4 is a left side elevation view thereof;

FIG. 5 is a right side elevation view thereof.

FIG. 6 is a top plan view thereof;

FIG. 7 is a bottom plan view thereof, and,

FIG. 8 is a top, front, right perspective view thereof, shown with the cap in an open position.

The broken lines in the drawings depict portions of the inhaler that form no part of the claimed design. Stippling and line shading have been used in the drawings to indicate a contrast in appearance.
